UNITED STATES PATENT OFFICE.

FREDERICK MUTIMER, OF ROCKFORD, ILLINOIS, ASSIGNOR OF ONE-HALF TO
THE ROCKFORD BOLT WORKS, OF SAME PLACE.

BOLT-TRIMMING MACHINE.

SPECIFICATION forming part of Letters Patent No. 427,437, dated May 6, 1890.

Application filed January 21, 1890. Serial No. 337,579. (No model.)

To all whom it may concern:

Be it known that I, FREDERICK MUTIMER, a citizen of the United States, residing at Rockford, in the county of Winnebago and 5 State of Illinois, have invented certain new and useful Improvements in Bolt-Trimming Machines, of which the following is a specification.

The object of this invention is to trim off 10 the flange or burr produced in the formation of the head, and which projects beyond the head of the bolt.

This invention consists of a stationary die 15 the size and conformation of the head of the bolt, a plunger for forcing the head of the bolt into the die, and means for operating the plunger, and in the various combination of elements and details of construction.

In the accompanying drawings, Figure 1 is 20 a plan view of a machine embodying my invention. Fig. 2 is a lengthwise vertical central section on dotted line *a*, Fig. 1, showing the parts in their retracted position. Fig. 3 is also a lengthwise central section on dotted 25 line *a*, Fig. 1, with the parts in their forward position. Fig. 4 is a transverse vertical section on dotted line *b*, Fig. 1. Fig. 5 is a transverse vertical section on dotted line *c*, Fig. 1, showing a face of the die. Fig. 6 is a transverse vertical section on dotted line *a*, Fig. 1, 30 showing the means of holding the plunger in position. Fig. 7 is a lengthwise central section of the die and support for the free ends of the bolts when long bolts are operated 35 upon. Fig. 8 is an isometrical representation of a bolt, showing the flange which my improved trimming-machine is designed to remove. Fig. 9 is an isometrical representation of a bolt which has had the flange removed.

40 The bed portion or frame of the machine in this instance consists of lengthwise side rails 1 and end bars 2 connecting the side rails, making a frame rectangular in form. The side rails have their inner faces in grooved 45 guideway form. In the guideways is fitted to slide a support 3 for the plunger and other removable parts. This forward end of the support is composed of vertical sides 4 and bottom 5, leaving a square lengthwise opening. An endwise-sliding movement is imparted to this support by a crank 6, supported in bearings 7, rising from the side rails

of the main frame, and which has a driving-wheel 8 mounted on its projecting end, which is connected to any prime mover by a belt 55 passing around the wheel. The center portion of the crank is fitted with a head 9, which slides in guideways 10 and 11 as it is revolved. The guideway 10 is an upright position of the support 3, and the guideway 60 11 is a separate piece joined to the support by a bar 12, as shown at Figs. 2 and 3, in such a manner as to make the guideways rigid with relation to each other. In the forward end of the support is secured a square block 65 13, having a cylindrical lengthwise opening 14, by bolts 15 passing through flanges 16 into the vertical sides 4 of the support. Within the cylindrical opening is fitted a tubular cylindrical shell 17 to slide therein. One 70 end 18 of this shell is closed and is of circular form and of somewhat larger diameter than the main portion of the shell, and has a central opening 19 of square form or of the conformation of the head of the bolt. This shell 75 17 is guided in its sliding movement within the block 13 by an arm 20, rising upward and passing through a slide 21, which is held in place by plates 22, secured to the flanges 16 by bolts 23. These plates permit an easy end- 80 wise-sliding movement of the slide 21, said slide and shell moving in unison. From the upper face of the slide rise ears 24, which are perforated and support a bar 25 by a bolt or rivet passing through the parts in such a manner as to permit the bar to oscillate. The forward end of the bar is bifurcated, forming two projecting ears 26, which are perforated and between which is pivoted a vertical sliding arm 27, having its edges beveled, which fit 85 28 in guideways in the outer face of the closed end of the shell 17. A handle 28 has a pivotal connection with the rear end of the bar 25 and the lower end of the handle resting on the upper face of the slide 21. To the support in 90 rear of the block 13 is secured a cylindrical spindle 29 by its square end 30 being clamped by a cross-plate 31, held by bolts 32 to the vertical sides 4 of the support. This cylindrical spindle enters the shell 17 in a close-fitting 95 manner, and from its end projects a cylindrical plunger 31 of a size small enough to pass through the opening in the closed end of the shell.

A die-plate 33 is bolted in position on the side bars 1, a face view of which is shown at Fig. 5. The opening 34 in the die-plate is of a size and conformation of the head of a bolt 5 and is in line with the opening in the closed end of the shell.

At Fig. 8 I have shown a bolt as it appears before the flange has been removed, with the machine in the position shown at Figs. 1 and 10. Such a bolt is placed in the opening in the closed end of the shell, so that its head will enter the opening. By moving the handle 28 forward its lower end will slide on the upper face of the slide 21, thereby depressing the 15 vertical arm 27, the lower end of which will come in contact with the head of the bolt, clamping it in the opening 19 and holding its shank in a horizontal position, as shown at Fig. 2. Motion is then imparted to the support in its forward direction through the medium of the crank, sliding head, and vertical guideways. This movement carries the parts supported thereby forward until the flange on the head of the bolt comes in contact 20 with the face of the stationary die. The shell 25 will then remain at rest and the further forward movement of the support forces the plunger against the head of the bolt and forces the head into the die, thereby shearing the flange from the head, which will leave it 30 in the condition shown at Fig. 9. The bolt and the parts will occupy the position shown at Fig. 3. As the support is withdrawn, all the parts supported thereby will move with it 35 until an uprising projection 34, or the slide 21, comes in contact with an arm 35, secured to the rear frame of the machine, which will cause the shell 17 and parts connected thereto to remain at rest while the plunger continues to move rearward, when the parts will 40 again occupy their former position. (Shown at Figs. 1 and 2.) While the shell is at rest the plunger moves rearward far enough to permit the insertion of the head of a bolt 45 into the opening in the closed end of the shell, as before described. When longer bolts are to be operated upon, then they can be safely supported by their heads alone. In the opening in the closed end of the shell I have con-

structed a support for their free ends, as 50 shown at Fig. 7, which is a slide 36 fitted to move in the lengthwise direction of the bed of the machine, and having an arm 37, with a socket in its end, and an operating-handle 38, by means of which the slide is moved. 55 The slide is moved by hand, so that the end of the bolt is received in the socket in the arm 37, and as the bolt is moved forward during the operations of removing its flange the slide will be forced forward until the bolt 60 is free to drop.

By this construction of a bolt-trimming machine I can remove the flange from the head of a bolt in a uniform and satisfactory manner, which will leave the head of the bolt 65 smooth on all sides.

I claim as my invention—

1. The combination of a die, means for holding a bolt, and a plunger, substantially as set forth.
2. The combination of a die, a movable head carrying a bolt, a plunger, and means for operating the head and plunger, substantially as set forth.
3. The combination of a die, a head supporting a bolt, a plunger, and means for operating the head and plunger, said head and plunger made movable independent of each other, substantially as set forth.
4. The combination of a die, and a support carrying a head and plunger, said support made movable to and from the die, substantially as set forth.
5. The combination of a die, a head and plunger having combined and separate movements to and from the die, substantially as set forth.
6. The combination of a die, a movable head and plunger, and a support for both ends of the bolt, substantially as set forth.
7. The combination of a die, a plunger, a head having an opening in its face, and means for holding the head of the bolt in said opening, substantially as set forth.

FREDERICK MUTIMER.
